CLAIM

The ornamental design for an electronic device with wireless dock slots, as shown and described.

DESCRIPTION

FIG. 1 is a perspective view of an electronic device with wireless dock slots;

FIG. 2 is a rear perspective view thereof;

FIG. 3 is a front perspective view thereof;

FIG. 4 is an alternate rear perspective view thereof;

FIG. 5 is a top, left, front perspective view thereof;

FIG. 6 is an exploded top, right, front perspective view thereof;

FIG. 7 is a top, right, front perspective view thereof;

FIG. 8 is a top, right, rear perspective view thereof;

FIG. 9 is a top plan view thereof; and,

FIG. 10 is a right side elevation view thereof.

The broken lines illustrating a peripheral device which docks into a dock slot in FIGS. 6 and 7 illustrate environment, while the remaining broken lines in the drawings illustrate portions of the electronic device with wireless dock slots that form no part of the claimed design.
